UNITED STATES PATENT OFFICE.

JAMES A. LAKIN, OF WESTFIELD, MASSACHUSETTS.

LOOP-FASTENING FOR WHIP-STOCKS.

SPECIFICATION forming part of Letters Patent No. 259,320, dated June 13, 1882.

Application filed April 3, 1882. (No model.)

To all whom it may concern:

Be it known that I, JAMES A. LAKIN, of Westfield, in the county of Hampden and State of Massachusetts, have invented a new and 5 useful Improved Loop-Fastener for Whip-Stocks, of which the following is a specification and description.

The object of my invention is to provide a cheap and effective fastening for securing the 10 loop to which the lash is attached to a whip stock or handle; and I accomplish this by the means substantially as hereinafter described, and illustrated in the accompanying drawings, in which—

15 Figure I is a side view of the ferrule. Fig. II is another side view, showing a front view of the holes in the device. Fig. III is a transverse section of the same at line A of Fig. II. Fig. IV is a side view of the same as applied 20 to the small end of a whip stock or handle with the lash-loop secured therein. Fig. V is a longitudinal section of the same at line B of Fig. IV. Fig. VI is a similar longitudinal section, showing a modification of the device 25 having only one hole in each side; and Fig. VII is a plan view of the loop which is to be secured to the stock or handle by the fastener.

In the drawings, 1 represents my fastener, which consists of a thin tubular piece, having 30 preferably four holes, as 2, therein—two on each side and nearly opposite each other, as shown clearly in Fig. I, and these holes should be elongated somewhat, as shown in Fig. II, in order that the loop, when secured therein, 35 may lie close and snug to the fastener. This tube 1 may be made of any suitable material, such as hard rubber, papier-maché, metal, or of any other material possessing sufficient strength; but I should prefer to use some material 40 which is light as well as strong, hard rubber possessing these qualities to the desired degree, and it should be made approximately smooth or plane on the inside.

The ordinary loop, as 3, is made generally 45 of suitable leather, and it is secured to the stock or handle by the fastener in the following manner: The stock or handle, as 4, may be slightly tapered at the end, and if a fastener having four holes is used one end of the 50 loop, as 3, is passed into that end of the tube nearest the holes, thence out through the first hole and in through the second, with the end

within the tube some little distance, as shown in dotted lines in Fig. V; and the other end of the loop is passed in at the same end of the 55 tube and through the holes 2 on the opposite side of the tube in precisely the same way. The end of the stock or handle is then forced through the tube from the opposite end, and the ends of the loop are thereby moved forward and doubled against the edge of the innermost hole 2; and if the stock is forced firmly into the tube the loose ends of the loop are wedged in so securely between the stock and the interior surface of the tube or fastener, as shown clearly in Fig. V, that it will be impossible to pull the loop out, and the lash may then be secured to the loop.

If a fastener having only two holes is used, one end of the loop is passed into the hole 2 70 on one side of the tube, projecting into the latter a little distance, and the other end is passed into the hole on the other side in the same way, and the end of the stock being forced into the tube from the other end, as before, the 75 two loose ends of the loop are forced forward and wedged in tightly between the stock and the interior surface of the tube, as shown clearly in Fig. VI. A fastener having two holes secures the loop to the stock quite as well 80 as one having four holes; but one having four holes presents a neater and more finished appearance, and on that account is perhaps more desirable.

The fastener, instead of being in the form 85 of a cylinder in cross-section, may, if desired, be many-sided, to give it a general cylindrical form, without departing in the least from the invention.

Having thus described my invention, what I 90 claim as new is—

1. A tube or ferrule provided with one or more openings on opposite sides thereof, and adapted to co-operate with a whip to secure the loop thereto, substantially as described. 95

2. The combination of a tube or ferrule provided with one or more openings on opposite sides thereof, a loop, and a whip-stock to receive said ferrule, substantially as set forth.

JAMES A. LAKIN.
